UNITED STATES PATENT OFFICE.

JOHN JACOB MILLER, OF CHICAGO, ILLINOIS, ASSIGNOR TO HIMSELF
AND ERNST PRUSSING.

IMPROVEMENT IN VALVES FOR STEAM-ENGINES.

Specification forming part of Letters Patent No. 43,949, dated August 23, 1864; antedated
February 15, 1863.

To all whom it may concern:

Be it known that I, JOHN JACOB MILLER, of Chicago, in the county of Cook and State of Illinois, have invented a certain new and useful Improvement in Valves; and I do hereby declare the following to be a full and exact description of the same, reference being had to the accompanying drawings, making part of this specification, in which—

Figure 1 is an axial section of a valve illustrating my invention. Fig. 2 is a horizontal section at *xx*, Fig. 1.

Similar letters of reference indicate corresponding parts in both figures.

My said invention consists in the use of a stationary cylindrical seat inclosed by a cylindrical valve adjustable in the length of its stroke, as hereinafter explained.

The invention further consists in an improved device for regulating the stroke of the valve.

To enable others skilled in the art to which my invention appertains to fully understand and use the same, I will proceed to describe its construction and operation.

A is a stationary cylindrical valve-seat, closed at its upper end, and near that end provided with a number of slots or apertures, *a a*, for the passage of the fluid. The said seat projects axially upward within a cast cylindrical casing, *B*, which is closed at its lower end by the base of the seat *A*, and at its upper end by a head, *C*, provided with a stuffing-box, *c*, through which works the valve-rod, to be hereinafter described. The casing *B* has a port, *b*, constructed and located in any suitable way.

D is a cylindrical valve fitted around the seat *A* and connected by a yoke, *E*, to a valve-rod, *F*, which works through the stuffing-box *c*, as before stated. The said valve-rod is screw-threaded for a considerable distance at its upper end, and formed with a longitudinal slot, *f*, the purposes of which will be presently explained.

G is a hand-wheel formed with an elongated hub, which is threaded upon the valve-rod.

H is a cross-head swiveled up the hub of the wheel *G*, and there retained by a nut, *I*.

J is a spring secured to the under face of the wheel *G*.

K is a pin projecting inward from the spring *J*. The said pin may pass through an aperture, *g*, in the hub and into the longitudinal

slot *f* in the valve-rod, as shown in Fig. 1, to secure the wheel from turning; or it may rest in a notch, *g'*, in the hub when the wheel is to be turned up or down.

Operation: In using the invention, the arm, beam, or rod by which the valve is to be operated, is attached to the arms *h* of the head *H*. The apertures *a* in the valve-seat are opened by the descent of the valve and closed by its ascent. To regulate the extent to which the valve will descend, and thereby the area to which the said apertures will be opened at each stroke, the spring *J* is drawn out, and its pin *K* rested in the notch *g'*. The wheel *G* may then be turned up or down, carrying with it the cross-head *H*. The higher the cross-head is set upon the valve the lower the valve will descend at each stroke, and vice versa. In this way the motion of the valve can be adjusted as desired, and being set to effect the required length of stroke, it is so held by setting the pin *K* through the aperture *g* into the slot *f*, by which means the wheel *G* is locked upon the valve-rod.

The packing of the stuffing-box *c* and valve *D* may be constructed in the manner described in my application of even date herein for Letters Patent for improvement in steam and other packing, the regulating-screws being supplied in one case by the customary screw-sleeve, *c'*, and in the other case by the screw attachment between the valve *D* and yoke *E*.

It is intended to use the above-described valve to regulate the flow of steam, water, and other fluids in any manner and place in which it may be found applicable.

Having thus described my invention, what I claim therein as new, and desire to secure by Letters Patent, is—

1. The combination of the fixed cylindrical seat *A* and cylindrical valve *D* with an adjusting-wheel *G*, or other substantially-equivalent device, to regulate the effective stroke of the said valve, as explained.

2. The spring *J* and pin *K*, used in the described combination with the aperture *g* in the wheel *G*, and the slot *f* in the valve-rod *F*, to lock the said wheel to the said rod or permit it to be turned up or down thereon, as and for the purpose explained.
